Primary Examiner — Michelle E. Wilson*Assistant Examiner* — Clese Moore, Jr.*(74) Attorney, Agent, or Firm* — Calfee, Halter & Griswold LLP(57) **CLAIM**

We claim the ornamental design for a bus, as shown and described.

DESCRIPTION

FIG. 1 is a rendered drawing of a front elevational view of a bus of the present design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a front/left perspective view thereof;

FIG. 7 is a rear/left perspective view thereof;

FIG. 8 is a line drawing of a front elevational view of a bus of the present design;

FIG. 9 is a rear elevational view thereof;

FIG. 10 is a right side elevational view thereof;

FIG. 11 is a left side elevational view thereof;

FIG. 12 is a top plan view thereof;

FIG. 13 is a top/rear/right perspective view thereof; and,

FIG. 14 is a top/front/left perspective view thereof.

The bottom view forms no part of the claimed design. The rendered drawings include surface shading that represents contour and not surface ornamentation. The broken line showing of wheels is for the purpose of illustrating environmental structure and forms no part of the claimed design.
